[57] CLAIM

The ornamental design for a finger-mountable marking instrument, as shown and described.

DESCRIPTION

FIG. 1 is a top, right front perspective view of a finger-mountable marking instrument showing my new design, with the cap member in a stored position;

FIG. 2 is a right side elevational view in an exploded condition, the left side being a mirror image thereof;

FIG. 3 is a right side elevational view, with the cap member in a closed position, the left side being a mirror image thereof;

FIG. 4 is a bottom plan view;

FIG. 5 is a front elevational view; and,

FIG. 6 is a rear elevational view thereof.

The fragmentary hand depicted by means of broken lines in FIG. 1 has been shown for illustrative purposes only and forms no part of the claimed design.
